CARL F. W. BUSCH, OF BELLAIRE, OHIO.

DROP-LIGHT ATTACHMENT.

1,103,395.

Specification of Letters Patent.

Patented July 14, 1914.

Application filed March 13, 1914. Serial No. 824,370.

To all whom it may concern:

Be it known that I, CARL F. W. BUSCH, a citizen of the United States of America, and resident of Bellaire, county of Belmont, and State of Ohio, have invented certain new and useful Improvements in Drop-Light Attachments, of which the following is a specification.

This invention relates broadly to gas-lighting fixtures, and specifically to a drop-light attachment.

The primary object of the invention is to provide a simple, inexpensive and novel means for attaching the flexible tubes of drop-lights to the chandeliers or bracket arms commonly employed.

A further object is to provide attaching means for drop-lights which does not require that the usual lamp-shade and the tubular supporting member therefor be permanently removed.

As is well known, the removal of the usual inverted gas lamp, with its shade, from a chandelier or cluster-bracket, as is required when a drop-light is attached in the usual manner, mars the appearance of such chandelier or bracket. It is therefore an object of the present invention to avoid the objection just referred to.

In describing the invention in detail, reference is had to the accompanying drawings, forming a part of this specification, in which—

Figure 1 is a central section of a shade and shade-supporting member of a common type, illustrating the application of my invention; Fig. 2 is a section on the line 2—2, Fig. 1; and Fig. 3 is a side elevation of the nipple.

Referring to said drawings, in which like designating characters distinguish like parts throughout the several views—1 indicates the arm of an ordinary gas-fixture, as a chandelier or bracket, the same terminating in a vertically disposed threaded stem 2; 3 indicates a tubular U-shaped supporting member for lamps of inverted-mantle type, and 4 a shade, all said elements being of a well-known or common form.

Instead of the means or mounting usually employed for attaching the supporting member 3, I provide a nipple 5 having an in-

ternally threaded socket 6 in its lower end adapted for the reception of the stem 2 of the arm 1, and provided with an externally threaded portion 7 adapted to receive thereon the lower interiorly threaded end of a sleeve 8 which is preferably formed of thin sheet brass and which is adapted to seat within the end of said supporting member 60 3 for supporting the latter. The bell 9 usually employed in connection with such fixtures may be employed, as shown, or may be omitted, if preferred. Formed integral with the nipple 5 at its upper end is a centrally disposed stem 10 of reduced size which is adapted to have closely fitted thereon the end of a flexible drop-light tube 11 which has been directed through the tubular supporting member 3, said end being preferably embraced by a metal thimble 12 whereby undue stretching or expansion of said end is prevented. A bore 13 leads vertically through the body of the nipple 5 and stem 10, communicating at one end with the bore 75 14 in the stem 2 of arm 1, and at the other end with the passage 15 through the drop-light tube.

From the foregoing it will be seen that the attachment of the drop-light tube is effected 80 through the shade 4 and tubular shade supporting member 3 and without the permanent removal of said elements from association with the arm 1.

What is claimed is—

1. A drop-light attachment comprising, in combination, the arm of a gas fixture, a nipple mounted vertically on said arm, a sleeve mounted on said nipple, a curved tubular shade-supporting member mounted on said sleeve, and a drop-light tube directed through said tube and connected to said nipple. 85 90

2. A drop-light attachment comprising, in combination, the arm of a gas fixture, a nipple mounted vertically on said arm, a sleeve mounted on said nipple, a curved tubular shade-supporting member mounted on said sleeve, and a drop-light tube directed through said tube and connected to said nipple, said nipple having a stem over which the end of said tube is fitted. 95 100

3. A drop-light attachment comprising, in combination, the arm of a gas fixture, a nip-

ple mounted vertically on said arm, and having exterior screw threads thereon, an integral upright stem provided on said nipple, a sleeve having its lower end mounted on said threads, a curved tubular shade-supporting member disposed upon the upper end of said sleeve, and a drop-light tube having its end fitted upon said stem, said

10 tube being projected through said tubular member.

In testimony whereof, I affix my signature in presence of two subscribing witnesses.

CARL F. W. BUSCH.
